UNITED STATES PATENT OFFICE.

JACOB SCHENCK, OF ST. LOUIS, MISSOURI.

DESIGN FOR A DOOR-STOP.

SPECIFICATION forming part of Design No. 27,867, dated November 16, 1897.

Application filed October 4, 1897. Serial No. 654,084. Term of patent 14 years.

To all whom it may concern:

Be it known that I, JACOB SCHENCK, of the city of St. Louis, State of Missouri, have invented a new and original Design for Door Stops and Shoes, of which the following is a full, clear, and exact description, reference being had to the accompanying drawings, forming a part hereof.

Figure 1 is a view in perspective of a door stop embodying my design. Fig. 2 is a horizontal section taken approximately on the line 2 2 of Fig. 1 and looking downwardly.

As shown in the drawings, the leading or material feature of my design for a door stop and shoe is a horizontal base-plate, a post extending upwardly from said base-plate, a top plate mounted upon the upper end of said post and parallel with the base-plate, and a flange extending upwardly from the top plate in a line transversely of the base-plate.

Referring by numerals to the drawings, 3 is the horizontal base-plate, which is rectangular in plan.

4 is a post extending upwardly from the horizontal base-plate, said post being T-shaped in cross-section, as shown in Fig. 2.

5 is the top plate, attached to the upper end of the post 4 in a line parallel with the base-plate 3, and 6 is the flange which projects upwardly from the top plate 5 in a line transversely of the base-plate 3. The flanges 7 and 8 extend upwardly from the side edges of the top plate 5 at the ends of the flange 6, said flange 6 being located approximately at the transverse centers of the flanges 7 and 8. 35

I claim—

The design for a door stop and shoe, substantially as herein shown and described.

In testimony whereof I affix my signature in presence of two witnesses.

JACOB SCHENCK.

Witnesses:

EDWARD E. LONGAN,
ALBERT J. McCUALEY.
